UNITED STATES PATENT OFFICE.

JAMES H. PAIGE, OF MANCHESTER, NEW HAMPSHIRE, ASSIGNOR TO LORIN EDSON CHARLES, OF BEDFORD, NEW HAMPSHIRE.

SUPPORT FOR CURLING OR CRIMPING IRONS.

SPECIFICATION forming part of Letters Patent No. 605,807, dated June 14, 1898.

Application filed October 11, 1897. Serial No. 654,867. (No model.)

To all whom it may concern:

Be it known that I, JAMES H. PAIGE, a citizen of the United States, residing at Manchester, in the county of Hillsborough and State 5 of New Hampshire, have invented certain new and useful Improvements in Supports for Curling or Crimping Irons; and I do hereby declare the following to be a full, clear, and exact description of the invention, such as 10 will enable others skilled in the art to which it appertains to make and use the same.

The invention consists of a holder or support for curling or crimping irons, and relates 15 to a peculiarly-constructed device for supporting the iron during the operation of heating the same.

The object of the invention is to provide a 20 rest or holder for the iron, and thus avoid the necessity of the user holding the iron in the flame of a gas-jet or lamp until the iron is sufficiently heated for use.

The invention will be hereinafter described 25 in such full, clear, concise, and exact terms that any person familiar with the art may make, construct, and use the same.

Referring to the drawings forming a part 30 of this specification, and in which like numerals indicate corresponding parts in the different views, Figure 1 is a perspective view of the holder. Fig. 2 is a sectional view showing it supported on the top of a lamp-chimney with the iron inserted in the holder, and Fig. 3 shows a modified form of the holder intended to be used on a gas-burner.

The holder is preferably made of a continuous 35 piece of wire of suitable size.

1 represents the base, 2 the body of the holder, and 3 the support, which sustains the entire device on the top of a lamp-chimney 40 and which may also be used as a rest or support for the crimping or curling iron.

The base 1 is a large single coil or convolution having its free end bent underneath, and which after being formed substantially 45 circular is bent radially from the circumference of the ring or base toward the center, and then formed into a series of convolutions smaller than the base, and finally bent horizontally, so as to form a loop 3, half of which 50 projects to each side of the series of smaller

convolutions, as shown. These arms of the loop or support 3 are of sufficient length to extend across and be supported by the top of a lamp-chimney.

The end of the wire at the top may be bent 55 at a right angle to the body of the loop or support 3, and a wooden handle may be secured thereto, as shown in dotted lines in Fig. 1, so that when the holder becomes hot it may be readily handled by the user. In this example of the invention the holder is laid across the top of a lamp-chimney, with the loop or support 3 resting on the edges of the chimney and the body portion 2, comprising the series of spirals or convolutions, substantially 60 tubular, and the base 1 will be suspended in the chimney. The crimping or curling iron is inserted in the opening or tube formed by the coils. The base being much larger than the convolutions above, it will center the 65 holder—that is to say, its larger circumference of the device should tilt or be moved to one side, would come into contact with the narrower walls of the lamp-chimney below its flaring top, and thus prevent the holder 70 from falling into the chimney.

The iron may be heated by laying it horizontally on the loop or support 1; but I prefer the manner of use shown in Fig. 2.

In Fig. 3 I have shown a modified form of 80 the holder adapted for use with a gas-burner. The base and body portion are precisely the same as the form just described, and shown in Fig. 2. The part of the holder 4 for the iron is, however, somewhat different.

The end of the wire at the top of the smaller 85 coils or spirals instead of being bent laterally or horizontally and formed into a loop is bent first vertically and then horizontally, as at 5, and this horizontal part or arm is formed with 90 two or more coils 6 6. In this instance the holder is used over a gas-burner, the burner being inside the smaller convolutions and the larger base resting on the gas-bracket, so that it will be firm and steady.

The curling or crimping iron is inserted 95 through the coils 6 6 in the lateral arm at the top and projects into the gas-flame and is thus heated.

While I have shown the holder made of 100

wire, and this is the preferred form, it is evident that it might be made of sheet metal, so as to have the same function and structure.

The holder is easily and cheaply made and 5 very handy and effective in use.

Having thus fully described my invention, what I claim as new, and desire to secure by Letters Patent, is—

1. A holder for curling or crimping irons 10 during the operation of heating, comprising an enlarged non-elastic base, a smaller substantially tubular body portion formed as a continuation thereof, and an arm or support at the top for receiving and supporting the 15 iron, substantially as described.

2. A holder for curling or crimping irons during the operation of heating, composed of a continuous piece of wire, having an enlarged base of a single coil, a series of smaller coils above the base, and a lateral loop or support 20 extending on each side of the body portion, substantially as and for the purposes described.

In testimony whereof I affix my signature in presence of two witnesses.

JAMES H. PAIGE.
